UNITED STATES PATENT OFFICE.

EUGENE L. CARILLON, OF BEDFORD, OHIO.

RADIATOR-THAWING MEANS.

Application filed November 2, 1920. Serial No. 421,266.

To all whom it may concern:

Be it known that I, EUGENE L. CARILLON, a citizen of the United States, residing at Bedford, in the county of Cuyahoga and 5 State of Ohio, have invented new and useful Improvements in Radiator-Thawing Means, of which the following is a specification.

The object of my present invention is the provision of a radiator embodying an overflow appurtenance whereby in the event of water freezing in the radiator, steam or hot water will be conducted down the overflow and will have the effect of thawing the primary passage and establishing circulation.

To the attainment of the foregoing the invention consists in the improvement as hereinafter described and definitely claimed.

In the accompanying drawings, hereby 20 made a part hereof:

Figure 1 is a vertical transverse section of a radiator equipped with my improvement.

Figure 2 is a detail view showing the arrangement of the overflow relative to a portion 25 of a cellular radiator.

Figure 3 is a detail view showing the arrangement of the overflow relative to a portion of a tubular radiator.

Similar numerals of reference designate 30 corresponding parts in all of the views of the drawings.

With the exception hereinafter set forth the radiator may be and preferably is of the ordinary cellular or tubular type.

35 In the carrying out of my invention I provide an overflow conduit 1 which extends from the upper portion of the interior of the radiator to a point below the radiator where it is adapted to discharge.

Manifestly in the event of the water in the 40 radiator freezing, steam or hot water will pass downwardly in the conduit 1 and by so doing will thaw the primary passage and re-establish circulation.

When the device is to be used in very cold 45 climates I deem it expedient to provide the conduit 1 at a point below its upper end with a lateral intake arm 2 through which any appropriate fluid agent may in a heated state be conducted to the conduit 1 to keep the 50 primary passage open and assure maintenance of circulation.

It will be apparent from the foregoing 55 that notwithstanding its practical advantages as set forth, my novel radiator appurtenance is extremely simple and inexpensive and therefore will not materially add to the cost of a radiator. It will also be apparent that inasmuch as nothing except steam and hot water is carried through the conduit 1 60 there is vertically no likelihood of the conduit 1 becoming clogged.

Having described my invention, what I 65 claim and desire to secure by Letters Patent, is:

A radiator characterized by a primary 70 passage and by a conduit open at its upper end and having said end arranged in the upper portion of the radiator and also having a discharge end located below the radiator, said conduit being relatively arranged to conduct steam or hot water downwardly through the primary passage, and being provided adjacent to its upper end with a lateral 75 intake arm through which a fluid agent may be supplied to the conduit.

In testimony whereof I affix my signature.

EUGENE L. CARILLON.
